SPRING LOADED VALVE

Wilfred Fourness, Oakland, Calif., assignor, by
mesne assignments, to Edward G. Burghard,
New York, N. Y.

Application September 22, 1930, Serial No. 483,593

2 Claims. (Cl. 230—185)

This invention relates to compressors, and more particularly to what is herein termed a spring loaded valve to be used with the mechanism of my copending case to a Compressor mechanism, Serial No. 318,736, filed November 12, 1928, and which is a continuation in part thereof.

In compressor mechanisms of the type above referred to, long or extended periods of inactivity cause oil, in which the mechanism is immersed, to seep between the walls of the piston and cylinder, and accumulate in the latter. When the mechanism is started up again after the period of inactivity, the oil in the cylinder must be first subjected to pressure, and if no means of ready egress therefor is provided, the mechanism will "stall". In addition, if there should be a sudden flooding of liquid on the return line, there would be a consequent sudden overloading or breakdown of the mechanism, unless some means are present for relieving against such an occurrence.

It is an object of this invention to provide a mechanism which will relieve the pressure set up by the compression of a liquid with the cylinder.

It is a further object of this invention to provide a valve mechanism which is responsive to unusual and abnormal pressures in the cylinder whereby the pressure therein is relieved.

It is a further object of this invention to provide a device simple in design and construction and inexpensive to manufacture.

My invention possesses many other advantages, and has other objects which may be made more easily apparent from a consideration of one embodiment of my invention. For this purpose I have shown a form in the drawing accompanying and forming part of the present specification. I shall now proceed to describe this form in detail, which illustrates the general principles of my invention; but it is to be understood that this detailed description is not to be taken in a limiting sense, since the scope of my invention is best defined by the appended claims.

Referring to the drawing:

Figure 1 is a sectional view of a reciprocating compressor mechanism embodying my invention; and

Fig. 2 is a fragmentary sectional view taken substantially along the plane 2—2 of Fig. 1.

The compressor mechanism is shown as located in a housing 10 having a removable end wall 11. The inlet for the compressor is provided through a pipe 12, and the outlet through a pipe 13.

The compressor proper is conveniently sup-

ported on wall 11, which has a shoulder 14 over which the main compressor body 15 is accommodated. The compressor can be driven by any appropriate source of motion, as by the aid of shaft 16 passing through the fluid tight packing gland 17 which is provided in a hub or boss 18 on wall 11. This shaft extends into the interior of the housing 10, and mechanically drives the piston devices utilized in the compressor.

The compressor body 15, as described in my copending application above referred to, has a substantially rectangular central portion 19, from which extend, in diametrically opposite directions, the cylinder blocks 20, 21. Each of these cylinder blocks has a large bore 22, 23, radial to the axis of the shaft 17, for the accommodation of the main pistons 24, 25 that are reciprocated therein. The blocks 20, 21 are also provided with valve bores 26, 27 that are parallel and close to bores 22, 23, and that accommodate the valve piston 28, 29 for the control of inlet and outlet ports for the cylinders 22, 23. All of the pistons 24, 25, 28, 29 can be provided with grooves such as 30 to facilitate oiling.

The pistons 24, 25 are reciprocated as follows: Shaft 16 is journaled inside of housing 10 in a cap or cover member 31 that fits over the end of the rectangular portion 19 to provide a fluid tight enclosure therein. Shaft 16 carries an eccentric portion 32 having a small flange 33. The eccentric is freely rotatable in an eccentric block 34. This block is embraced by a frame slide 35 in a manner fully described in my above mentioned copending application; that is, a rotation of eccentric 32 causes a side to side motion of block 34, and a consequent vertical reciprocation of slide 36. As pistons 24, 25 are mechanically fastened to slide 35, as by a dovetailed connection 36, the reciprocation of the slide causes a reciprocation of the pistons and a consequent compression of the fluid fed to the compressor.

The fluid to be compressed in the cylinders 22, 23 enters therein through ports 37, 38 which are open for a time that falls within the time corresponding to the piston movement out of the cylinder space. On the compression stroke, port 37 or 38 is closed, and the fluid is compressed in the cylinder space. After a definite piston movement into the cylinder space, port 37 or 38 again opens, but now communication is established with outlet passages 39 or 40. Since pistons 24, 25 are on opposite sides of slide 35, one of them is on its suction stroke while the other is on its compression stroke. Each of the cylinders 22, 23 has a cap referred to as by 41, 42 in order to define the

cylinder spaces, and for a purpose to be herein-after described.

The caps 41, 42 are formed of main body members 43, 44 having central depending portions 45, 46 extending into and snugly contacting with the inner walls of the cylinders. An opening extends through each main body member and terminates at the lower portion thereof in a valve seat 47, 48. Valve closures 49, 50 are arranged to coact with 10 the valve seats to form a valve. The valves are maintained in a normally closed position by means of strong springs 51, 52 encircling the valve stems 53, 54 and acting against the valve closure members 49, 50. Plugs 55, 56 are screw-threaded 15 into the upper portion of the openings extending through the main bodies 43, 44 and act to confine the springs 51, 52. Communication is established between the cylinders 22, 23 and the space 57 by means of passageways 58, 59 in a manner to be 20 hereinafter described.

It is to be understood, that piston valves 28, 29 are mounted on an eccentric 60 in a manner similar to pistons 24, 25; and that by appropriate angular arrangement between eccentrics 32 and 25 60, the proper sequence of the valve opening and closing actions with respect to the movements of the pistons 24, 25, can be secured. As the action of the pistons and piston valves to control the ports 37, 38, 39, and 40 have been fully set forth 30 in my copending case above referred to, no further description thereof is deemed necessary. In the drawing, no attempt is made to indicate the correct lead or lag of one eccentric with respect to the other, however, it is to be understood that 35 such lead or lag is essential to obtain the proper opening and closing of the inlet and outlet ports.

In order to fully comprehend the function of the spring loaded valves 49, 50, particular attention is directed to the relation of piston 25 and 40 piston valve 29 to port 38. Let us assume that the compressor has been inactive for some time, and that oil has seeped into the cylinder 23. It will be noted that piston 25 is just beginning its compression stroke and in that position port 38 45 is closed by piston valve 29. As the piston 25 begins compressing, it first acts to subject the oil to pressure in cylinder 23. If there were no provisions for the spring valve, there would be no escape passageway provided for the compressed oil, and the pressure built up in the 50 cylinder 23 would immediately stall the motor. However, by my arrangement, the pressure built up by the compressed oil is sufficient to open the valve closure 50 against the action of the spring 52, and thereby permits the oil to flow 55

out of the relief port 50. Of course during normal running conditions, very little oil is in the cylinder 23 and only the expanded refrigerant is compressed. The pressure set up during this period is not sufficient to overcome the action of the spring 52 and the compressed gas flows out of the port 38 which is opened when the piston valve 29 has been moved in proper cyclical sequence with respect to piston 25.

It is not an infrequent occurrence for liquid 10 to be carried into the inlet 12 along with the gas refrigerant. The liquid would then flow into the cylinder 22 and also into cylinder 23 through the medium of the pipe connection 61, and cause a sudden overloading or breakdown of the compressor. However, the spring loaded valve would 15 operate to relieve the pressure set up by this return compressed liquid in a manner hereinabove described.

I claim:

1. In a mechanism for compressing a gaseous refrigerant, a cylinder, a piston movable therein for compressing the refrigerant in the interior of the cylinder, means forming an outlet valve from the cylinder, means whereby a lubricant is supplied to the cylinder, a yielding valve closure cooperating with a port in the cylinder wall, said port being in communication at all times with the cylinder interior, said closure being so constructed that the closure opens only upon abnormal pressure in the cylinder and remains closed during normal operation of the mechanism, and means forming a collecting space communicating with said port when the closure opens, said space also serving as a reservoir for the lubricant to the 35 cylinder.

2. In a mechanism for compressing a gaseous refrigerant, a cylinder, a piston movable therein for compressing the refrigerant in the interior of the cylinder, a positively driven valve mechanism controlling an outlet from the cylinder in timed relation to the piston movement, means whereby a lubricant is supplied to the cylinder, a valve closure cooperating with a port in the cylinder wall, said port being in communication at all times with the cylinder interior, means for urging the valve closure to closing position with a force such that abnormal pressures only, can open the closure, and means forming a collecting space communicating with said port when the closure opens, said space also serving as a reservoir for the lubricant supplied to the cylinder.

WILFRED FOURNESS.
